UNITED STATES PATENT OFFICE.

HARRY NETHERWOOD, OF WARRINGTON, ENGLAND.

STOP-MOTION FOR VELVET AND LIKE PILE CUTTING MACHINES.

1,292,020.

Specification of Letters Patent.

Patented Jan. 21, 1919.

Application filed June 1, 1916. Serial No. 101,115.

To all whom it may concern:

Be it known that I, HARRY NETHERWOOD, a subject of King George V of Great Britain, residing at Warrington, in the county 5 of Lancaster, England, have invented a new and useful Improvement in Stop-Motions for Velvet and like Pile Cutting Machines, of which the following is a specification.

This invention relating to stop motions 10 of velvet and like pile cutting machines such as set forth in the specification of U. S. Patent No. 790577 and particularly to the improvements in such stop motions described and claimed in the specification of 15 U. S. Patent No. 876462 has for its object the provision of improved means whereby the supplementary guide, shown and described in such last named specification, is dispensed with and the cutter with its guide 20 and holder act alone for effecting the stoppage of the machine when the cutting knife enters the "slip race" or is otherwise deflected or caused to assume an abnormal position through excess of pressure of the fabric thereon during the cutting operation, or 25 through other causes.

The improvements herein have no reference to knives of ordinary type which, with their guide portions, it has been proposed 30 to secure to upwardly projecting lugs loosely mounted on supporting bars and adapted to be moved into engagement with contact members when the diversion of the knife causes it to be swung in either direction.

35 My invention will be described with reference to the accompanying drawing, in which:—

Figure 1 is an elevation of a knife or cutter holder and parts constructed according to my invention;

Fig. 2 is a plan view of Fig. 1;

Fig. 3 is a section taken on line A—B, of Fig. 1 and

Fig. 4 is a part elevation showing a modified construction of my improvements.

Referring to the drawing, and firstly to Figs. 1, 2 and 3, *a* represents the knife, *b* the knife guide in which the knife is frictionally held and *c* the guide holder which 50 is, according to my invention, secured to the knife guide by soldering or like means. The guide holder *c* has in this instance pivotally secured thereto a contact plate *d*. For this purpose the guide holder has an upwardly

extending portion *c'* to which the lower portion of the contact plate *d* is pivotally secured by means of the screws *e*. The contact plate is suitably shaped at its lower end to form a shoulder *d'*, a lip or bent portion *d''* extending rearwardly to act as a stop 60 against the portion *c'* of the guide holder. The contact plate *d* is adapted to engage with the contact maker *f* of the ordinary stop motion and the knife and guide are carried by a spindle *g* which is capable of 65 being readily applied to or removed from the tilting cutter holder *h* as ordinarily. Suitable insulating material is applied to insulate the parts where required.

The knife guide *b* and guide holder *c* with the spindle *g* for pivoting same in the tilting cutter holder *h* thus form a single movable part which can be easily handled and the guide and knife or cutter inserted in the race to be cut. So long as the guide and 70 knife or cutter run truly in the race, the upwardly extending projection or contact plate *d* remains in engagement with the contact maker *f* to maintain the electric circuit but should the knife or cutter be deflected 75 from its course and enter the "slip race" or be forced by excessive pressure of the fabric into an abnormal position, the movement of said knife causes the guide also to move with it whereby the upwardly extending 80 projection *d* is moved clear of the contact maker *f* thus breaking the circuit and bringing about the stoppage of the machine in 85 the usual manner.

Instead of a separate contact plate *d* pivotally mounted to the upwardly extending portion *c'* of the guide holder *c* we may construct the guide holder *c* and contact plate *d* in one piece, as shown at Fig. 4.

By the means described, I dispense with 95 the supplementary guide and with the contact pieces between the supplementary and ordinary guides hitherto employed and simplify the parts, this being of considerable advantage to the operator.

Having thus described my invention, what I claim as new and desire to secure by Letters Patent is:—

1. A device of the character described, comprising a guide-holder, a contact plate 105 secured thereto and a second contact member in operative relation with said first contact plate.

2. A device of the character described, comprising a guide-holder, a knife-guide, a contact plate pivotally secured to said guide-holder and a second contact member located above said first contact plate.
3. A device of the character described, comprising a guide-holder, a knife-guide, a contact plate pivotally secured to said guide-holder and provided with a stop arranged to engage and disengage said guide-holder and a second contact member located above said first contact plate.
4. A device of the character described, comprising a guide-holder, a knife-guide secured thereto, a contact plate pivotally secured to said guide-holder and provided with a rearwardly extending lip arranged to engage and disengage said guide-holder and

a second contact member located above said first contact plate.

5. An article of the character described, comprising a guide-holder having a central raised portion a knife-guide secured to said guide-holder, a contact-plate pivotally secured to said raised portion and provided with a shoulder and lip arranged to engage and disengage said raised portion and a second contact member located above said contact plate.
